UNITED STATES PATENT OFFICE.

ARTHUR H. PITNEY AND JACOB W. OGDEN, OF STAMFORD, CONNECTICUT, ASSIGNORS
TO UNIVERSAL POSTAL MACHINES CORPORATION, OF STAMFORD, CONNECTICUT,
A CORPORATION OF DELAWARE.

REGISTER FOR POSTAGE-MARKING MACHINES.

Application filed June 7, 1922. Serial No. 566,593.

To all whom it may concern:

Be it known that we, ARTHUR H. PITNEY and JACOB W. OGDEN, citizens of the United States, residing at Stamford, in the county of 5 Fairfield and State of Connecticut, have invented certain new and useful Improvements in Registers for Postage-Marking Machines; and we hereby declare that the following is a full, clear, and exact description thereof, reference being had to the accompanying drawings, which form part of this specification.

This invention is a novel improvement in postage meters and mail marking machines 15 of the type shown in the Pitney Patents #1,273,793 of July 23rd, 1918, Reissue #14,916 dated July 13, 1920, and #1,370,668, granted March 8th, 1921.

The object of the present invention is to 20 provide a simple counting mechanism or register, to be attached to mail marking or sealing machines, for the purpose of printing postage stamps directly on mail matter and registering the number of pieces so 25 printed. It is designed for use by merchants, manufacturers, and corporations whose daily mailings do not justify the use of the more elaborately constructed postage meters such as shown in said patents.

30 The invention provides a novel and practical device for printing such required indicia on mail matter as will obviate applying ordinary postage stamps thereto, and the present necessity of verifying the mailer's 35 count on each batch of mail and at the same time, with the aid of two ordinary commercial counters, afford ample and adequate protection to the Postoffice Department; and will make it possible for a larger number of 40 patrons to avail themselves of postage permit privileges, and thereby assist in increasing the efficiency of the department by eliminating a great deal of time consuming labor after the mail reaches the postoffice.

45 The present invention also is adapted to be used in connection with machines of the general type shown in Patent #1,370,668, and is to be substituted therein in place of the so-called "meter" shown and described 50 in the aforesaid patent and when so placed in said machine will be operated by the mechanism of said machine and record the

total amount of the stamps applied by the machine; and also the number of times the machine is operated after each setting.

55 The novel register consists of two counters or sets of consecutive numeral wheels each of which is connected by gearing to the spindle which carries the revolving printing die. One of these counters is continuous in 60 its action recording each revolution of the die until its limit (say 9,999,999) is reached, and then commences again at 0. This counter records the total amount of stamps applied. The other counter is capable of being cleared 65 or set back to zero at any time and is used to keep a record of the number of impressions made. The key by which the clearing of the latter counter is accomplished is held by the post office by which the permit 70 is granted.

75 In the accompanying drawings we have illustrated one form of mechanism embodying our invention, and an understanding thereof will enable others to adopt and use the invention, but we do not consider the invention restricted to the specific devices shown as changes may be made therein within the scope of the invention as set forth in the appended claims; to which we refer for 80 summaries of the essentials of the invention and novel combinations of parts for which protection is desired.

In said drawings:

Fig. 1 is a top plan view of the detachable 85 printer and register.

Fig. 2 is a side view thereof.

Fig. 3 is a horizontal sectional view on the line 3—3, Fig. 4.

Fig. 4 is a vertical sectional view on the 90 line 4—4 Fig. 3.

Fig. 5 is a transverse sectional view on the line 5—5 Fig. 4.

95 In the construction shown the register consists of a hollow base member 1 closed by a bottom plate 1^a and having formed with or securely attached thereto a standard 1^a having an arm 1^b on its upper end in which is formed an upper bearing 1^c for the spindle 2^a of the printer 2 hereinafter referred to 100 and in the upper plate of the base is formed a lower bearing 1^d for said spindle. The lower side and one end of the base is closed by a slide plate 1^e which engages suitable

guide grooves in the side walls of the base plate 1 and which when pushed into its proper place is locked in position by a spring actuated pawl 1⁴ which is pivoted on a transverse rod 1⁵ in the base and is pressed into engagement with a notch in the plate by a spring 1⁶ as shown in Fig. 4, thereby effectually locking the plate against retraction. The said latch is inaccessible when the plate 1⁶ is slid home and can only be disengaged by making a hole through the plate 1⁶ thereby either destroying it or evidencing tampering therewith.

The printer 2 may be of any suitable construction, and is preferably such as described in my aforesaid patent. It is mounted upon the spindle 2^a and rotated thereby. The spindle 2^a depends into the base and has on its lower end, within the hollow base 1, a gear 2^c having a hub 2^b provided with a notch 2^d which notch is adapted to be engaged by a tooth 66^a on a lever 66 pivoted on a pin 67 in the base, at one side of the gear, said lever having an elongated slot through which the hub of the gear 2^c passes. The free end of lever 66 is adapted to be engaged by a spring 66^b on a pin 69 mounted in the casing and normally pressed outwardly to hold the tooth 66^a in engagement with the notch 2^d, the outer end of the pin 69 lying inside the end wall of the base 1, as indicated in Fig. 3. This latch 66 is adapted to lock the spindle against rotation when the register is removed from the machine; but when the register is placed in a machine like that shown in my said patent a pin on the machine (not shown in the drawings) engages the pin 69 and pushes it back sufficiently to oscillate latch 66 and disengage tooth 66^a from gear 2^c thus freeing the spindle in the manner in which the printer is released as explained in my aforesaid patent.

To the lower end of the spindle 2^a is attached a coupling member 47 having a tongue 47^a to engage a corresponding slot in a coupling member on the drive shaft of the printing machine to which the device is attached, as shown in my Patent #1,370,667, so that the spindle will be rotated once for each printing operation of said machine, as explained in said patent. A block 1ⁱ it fastened by screws to the bottom of the base 1 to receive the lower end of the spindle and 55 also act as an end stop to the plate 1⁶ as in said patent.

Mounted upon the base 1 at the side of bracket 1^a opposite the spindle is a casing 3 which is preferably made of metal and is closed at top, sides and outer end, and its end is closed by the vertical portion of the bracket 1^a, adjacent the printer. This casing is fastened by screws 3^a to the base 1, and as these screws are only accessible from 65 within the base 1, and therefore the casing

cannot be removed after the plate 1⁶ is put in place and locked as described. The casing has two small openings 3^b and 3^c in its top through which the numerals appearing on the total register or counter 5, and sub-totaling counter 6 may be respectively seen.

The sub-totaling counter 6 has an end extension 6^a which is closely fitted into a small opening in the outer end wall of the casing 3 which permits a key 6^b to be inserted into the cylinder of the lock or barrel of the sub-total counter, whereby the numeral wheels on the counter 6 may be set to zero when desired.

These counters 5 and 6 may be of any suitable construction and are illustrated as counters of a type which may be purchased in the market, and are provided with numeral wheels and devices to "carry over" from one wheel to the next in the usual manner. The counter 5 is entirely inaccessible and is adapted to register the total number of operations, or rotations, of the printer 2. The counter 6 can be re-set at will by the person having the proper key 6^b, controlling its lock; and register 6 is adapted to register or indicate the number of operations performed by the machine for any given period of time.

The counters 5 and 6 are mounted on a suitable frame 7 within the casing 2, and securely fastened to the base plate 1, the fastening screws not being accessible after the plate 1⁶ is in place. The counters are driven by suitable devices from the spindle 2. Preferably the counters are simultaneously operated by the means illustrated in the drawings. As shown, the counter 5 has a worm gear 5^b on its shaft meshing with a worm 5^a mounted on a spindle 5^d journaled in the frame 7 to the inside of the worm 5^b, and spindle 5^d has a pinion 5^c on its lower end meshing with a gear 7^a mounted on a spindle 7 journaled in the base 1. The shaft of the counter 6 has a worm gear 6^b meshing with a worm 6^a on a spindle 6^d journaled in the frame 7 to the inside of the worm gear 6^b, and spindle 6^d has a pinion 6^c on its lower end meshing with the gear 7^a. The spindle 7 extends into the base 1 and has a gear 7^b on its lower end meshing with an intermediate gear 8^a, journaled on a stud 8 in the base 1, said intermediate gear 8^a directly meshing with the gear 2^c.

The train of gears 2^c, 8^a, 7^b, 7^a communicate the movements of the printer spindle 2^a to the counter actuating spindles 6^d, 5^d, and the gear ratios are so designed that the units wheel of each counter will be shifted one number for each revolution of the printer spindle. Attached to the intermediate gear 8^a is a ratchet 8^b which is engaged by a spring pressed pawl 8^c to prevent the counter shafts being turned backward at any time.

When constructed and arranged as described all the interior working parts are inaccessible and the attachment can be handled as a unit and can be applied to a postage mail marking machine such as shown in my Patent #1,370,668 by removing the "meter" from such machine and inserting this attachment in its place. The base 1 of the attachment should be made to correspond 10 in size and form with the socket or receptacle in the machine to which it is to be applied. In the example shown the base 1 of the attachment corresponds in shape and size to the base 41 of the meter shown in said patent, and therefore said attachment can be substituted in that machine for the meter shown in said patent; and when so substituted the pin 69 would be pushed inward by the pin on said machine (described and 20 shown as 8 in said patent), thereby releasing the spindle, and at the same time the rib 47^a on the spindle will engage the related coupling member in said machine (described and shown as 20 in said patent), so that the spindle 2^a of the attachment will be operated just as the spindle of the printer as 25 described in said patent.

When removed from the machine the spindle 2^a is locked automatically against 30 further rotation by the latch lever 66 engaging gear 2^c and the register cannot be tampered with. When the meter is in position in the machine the register 6 will show up 35 the operations performed by the machine between one time of inspection and another; while the register 5 will show the total number of operations which are performed by the machine.

Permits to mail matter without stamps 40 affixed are now granted by the Post Office Department, as provided by present section 459 Postal Laws and Regulations. Paragraph 5, section (a) provides that "the postmaster may receive from the mailer a deposit 45 of money in advance (for which a special receipt shall be given) sufficient to pay for more than a single mailing. The deposit shall be charged with the proper amount of each mailing; but if the amount in hand is 50 not sufficient at any time to cover the postage due on the entire mailing, the excess shall be held until an additional deposit is made."

The regulations also provide that all mail matter presented for mailing without stamps 55 affixed, and on which the required indicia has not been printed by a device having mechanism that may be set for designated number of impressions showing the amount of postage paid and which, after the exhaustion 60 of such number of impressions, automatically locks itself so that no further impressions can be made until the mailer has brought the printing or numbering head or meter to the post office and has had the 65 postmaster re-set the mechanism for a given

number of impressions, the amount of postage to cover the number of such impressions to be paid at the time the device is set—shall be delivered at a place designated by the postmaster where the mailer's count or 70 statement of mailing is verified. This can be done with the aid of a cancelling machine, to which a counting device is attached, after the ink roller has been removed. If a cancelling machine is not available the matter 75 presented must be counted by hand. As both these methods of verifications require time, and have to be performed usually during the rush hours of the post office, it becomes apparent that the use of the so-called 80 permit privilege, as applied to first class mail, would actually retard instead of expedite its dispatch after reaching the post office, unless suitable means are provided for printing the required indicia on the mail 85 and for registering the total number of operations performed in any given period of time, and for also registering the total number of operations and adequately protect the Post Office Department. Our invention provides a very simple means for doing this and 90 assists in increasing the efficiency of that department by eliminating a great deal of time and labor in preparing the mail after it is deposited in the post office. 95

The method of operation is as follows:

The mailer, after being assigned a permit number, presents his register, to which the die and post-mark are attached, to the postmaster with check or currency as a deposit 100 against which his daily mailing will be charged, it being assumed that the amount of the deposit will exceed that of his average daily mailings.

After receiving the money the postmaster 105 sets the sub-total counter 6 back to zero, and removes and keeps the key, and hands the register back to the mailer. The register is then taken to the mailer's office and placed on the machine. Each piece of mail passing 110 through the machine increases both counters one unit. The total counter 5 will indicate up to 10,000,000 before it automatically 115 clears to zero. The sub-total counter 6 being merely intended to count each mailing, continues to increase until the end of the day, at which time the device is detached from the machine and taken to the post office together with the last batch of mail, and a corresponding statement presented to the proper 120 clerk who checks the amount indicated on the counter 6 with the amount indicated on the total register 5 and any slips accompanying previous mailing for the day. Everything being found correct the post office official takes the key, 6^c which the post office 125 retains, and sets the counter 6 back to zero; so that the mailer may re-start counting his mail at zero the following day, sufficient money being deposited with the post office by 130

the mailer to cover the next daily mailing before the postal clerk returns the device to the mailer for further use.

The regulations provide that at any time 5 the amount of prepaid permit mail presented exceeds the amount of money on deposit, the excess quantity shall be held until an additional deposit is made.

While we have described the invention as 10 applicable to the postage meter machines as shown in the Pitney patents aforesaid, it will be obvious that the invention could be readily adapted for use with other types of machines, and therefore we do not consider 15 the invention restricted to use with said patented machines.

What we claim is:

1. An attachment for the purpose specified, comprising a base, a rotatable printer 20 mounted thereon; a casing on the base beside the printer; a total counter and a sub-total counter in the casing; gearing between the printer and said counters whereby each counter is turned one unit for each rotation 25 of the printer; and means for locking the printer against rotation when the attachment is removed from the machine whereby it is operated, and for releasing the printer when the attachment is placed in the ma- 30 chine.

2. In an attachment as set forth in claim 1, key controlled means whereby the sub- 35 total counter may be reset without opening the case.

3. In an attachment as set forth in claim 1, a spindle in the casing for driving each counter; a driving gear simultaneously meshing both spindles; and gearing for operating said driving gear from the printer.

4. In an attachment as set forth in claim 1, each counter having a worm gear on its shaft; a worm spindle engaging such gear; a gear simultaneously operating both spindles; and gearing between said gear and the 45 printer, substantially as described.

5. An attachment for the purpose specified, comprising a hollow base; a casing mounted thereon; a total counter and a sub-total counter arranged side by side in said casing; a spindle journaled on said base beside the casing; a printer carried by said spindle; gearing between said spindle and each of the said counters; and means whereby the spindle is automatically locked when 55 the device is removed from the machine which operates it and automatically released when it is replaced in the machine.

6. In an attachment as set forth in claim 5, key controlled means whereby the sub- 60 total counter may be reset.

7. In apparatus as set forth in claim 1, a spindle in the casing for driving each counter; a driving gear simultaneously operating both spindles; and gearing for operating 65 said driving gear from the printer.

8. In apparatus as set forth in claim 5, each counter having a worm gear on its shaft; a worm spindle engaging such gear; a driving gear simultaneously operating both spindles; and gearing in the hollow base 70 between the driving gear and the printer spindle, substantially as described.

9. An attachment for the purpose specified; comprising a base; a rotatable printer; a casing on the base; a pair of counters in 75 the casing; a worm gear on each counter shaft; a worm spindle engaging each worm gear; a driving gear in the casing simultaneously operating both spindles; and gearing in the base for actuating said driving gear 80 from the printer spindle, substantially as described.

10. In an attachment as set forth in claim 9, key controlled means whereby one of the 85 counters may be reset.

11. In an attachment as set forth in claim 9, a plate for closing the hollow base and preventing access to the gearing or casing; and means for indetachably securing said plate in closed position.

12. An attachment for the purpose specified, comprising a base, a rotatable member mounted thereon; a total counter and a sub-total counter; means whereby each counter is turned one unit for each rotation of the 90 member; and means for locking the member against rotation when the attachment is removed from the machine whereby it is operated, and for releasing the member when the attachment is placed in the machine.

13. In an attachment as set forth in claim 12, key controlled means whereby the sub-total counter may be reset without opening the case.

14. In an attachment as set forth in claim 12, a spindle in the casing for driving each counter; a driving gear simultaneously meshing both spindles; and gearing for operating said driving gear from the said member.

15. In an attachment as set forth in claim 12, each counter having a worm gear on its shaft; a worm spindle engaging such gear; a gear simultaneously operating both spindles; and gearing between said gear and the 115 member, substantially as described.

16. An attachment for the purpose specified, comprising a rotatable printer; a total counter and a sub-total counter; means whereby each counter is turned one unit for each rotation of the printer; and means for locking the printer against rotation when the attachment is removed from the machine whereby it is operated, and for releasing the printer when the attachment is placed in the 120 machine.

17. In an attachment as set forth in claim 16, key controlled means whereby the sub-total counter may be reset without opening the case.

18. In an attachment as set forth in claim 16, a spindle in the casing for driving each counter; a driving gear simultaneously meshing both spindles; and gearing for operating said driving gear from the printer. a gear simultaneously operating both spindles; and gearing between said gear and the 10 printer, substantially as described.
19. In an attachment as set forth in claim 16, each counter having a worm gear on its shaft; a worm spindle engaging such gear;

In testimony that we claim the foregoing as our own, we affix our signatures.

ARTHUR H. PITNEY.
JACOB W. OGDEN.
